UNITED STATES PATENT OFFICE.

FRANK H. MILLER, OF MILWAUKEE, WISCONSIN.

MICROMETER-CALIPER.

1,388,740.

Specification of Letters Patent. Patented Aug. 23, 1921.

Application filed October 15, 1920. Serial No. 417,069.

To all whom it may concern:

Be it known that I, FRANK H. MILLER, a citizen of the United States, and resident of Milwaukee, in the county of Milwaukee and State of Wisconsin, have invented certain new and useful Improvements in Micrometer-Calipers; and I do hereby declare that the following is a full, clear, and exact description thereof.

10 My invention has reference to an improvement in micrometer calipers, and more particularly to calipers having or adapted to have measurement-indicating means reading to one thousandths of an inch more or 15 less.

My object is to provide these improvements in such a manner that it may be read more easily and quickly than others of its class. To accomplish this, I have provided 20 two sets of graduations, one on a rotating member which indicates the decimal fractions—that is, one-fourth, one-eighth, one-sixteenth, or smaller common subdivisions of an inch, and the other on a stationary 25 member which indicates readings to one ten thousandths of an inch.

A further object of my invention is to provide a measuring device of the character described which is adapted to register 30 exactly and without computation the common as well as decimal fractional parts of an inch.

A further object of my invention is to provide an improved means for moving the 35 work-engaging members of the tool into engagement with the work.

In the accompanying drawings:

Figure 1 represents a longitudinal sectional view thereof, with a portion of the 40 micrometer in elevation.

Fig. 2 represents an elevation of the micrometer, showing the several graduations,

Fig. 3 is a plan view of the rotation thimble as extended in the flat, with the rows of 45 numerals therein expressing different graduations,

Fig. 4 is an end view of the rotating thimble showing the graduations thereon, and

50 Fig. 5 is a similar view of the stationary barrel, showing the graduations thereon.

Referring to the drawings in detail, the numeral 1 designates the usual U-shaped frame, which is provided with the anvil 2, 55 same forming the stationary member of the caliper.

The opposite end of the U-shaped member has therein an internal threaded opening in which is screwed the threaded shank 3 of the disk 4, same having arranged thereon 60 the tubular sleeve 5, the free end of which is threaded internally and having screwed therein the member 6.

The member 3 is provided with a plurality of tapered fingers 7 which are adapted to be 65 wedged snugly against the measuring end of the spindle 8, which moves back and forth in the bore 9 of the disk and shank, by the locking element 10.

The sleeve 5 has movable thereon a second sleeve 11, the outer end of which is closed and has secured thereto the spindle 8, a portion of which is threaded, as at 12, and adapted to engage the threads of the bore within the member 6. The member 6 has 75 extending outwardly therefrom a split sleeve 13 which is externally threaded and provided with the locking nut 14. By this structure, compensation for wear is provided.

Secured to the disk 4 is a tube member 15 which is provided with a sight opening 16 as shown in Fig. 2.

The ends of both the sleeve 11 and the tube 15 are beveled and have thereon graduations, as shown in Figs. 4 and 5.

The sleeve 11 is provided with a milled exterior, as at 17.

Referring now to the scales or graduations upon the sleeve, I desire to call your attention first to Fig. 3, and in this I have shown the sleeve 11 as being divided into fourths, eighths, sixteenths, thirty-seconds and sixty-fourths of an inch.

These graduations coöperate with the 95 graduations on the end of the tube 15.

The graduations on the sleeve 5 indicate the thousandth part of an inch and coöperate with the graduations on the end of the sleeve 11.

Thus, it will be apparent that as the sleeve 11 is rotated, the fractional part of an inch will be recorded by the graduations of the sleeve being brought into line with the zero mark on the beveled edge of the tube 15, 105 which is graduated in thousandths to indicate the variations of the measurement of various settings. Also, by the coöperation of the graduations on the sleeve 5 and the end of the sleeve 11, the thousandths and 110 decimals in various numbers are indicated. For instance, should the user desire to set

the micrometer to $\frac{5}{64}$ ths of an inch, the sleeve 11 is rotated until the numeral 5 on the 64th line registers with the zero mark upon the beveled edge of the tube 15.

5 From the foregoing, it is thought that the construction, operation and many advantages of the invention described herein, will be apparent to those skilled in the art, without further description. It is to be understood that various changes in the details of construction may be resorted to without departing from the spirit or sacrificing any of the advantages of the invention.

Having thus fully described my invention, 15 what I claim as new, and desire to secure by Letters Patent, is:—

1. A micrometer caliper comprising a U-frame, a sleeve fixed in one end of said frame, a second sleeve spaced from and in 20 closing the first sleeve and having an opening therein, a third sleeve movable between the first two and having a measuring spindle fixed thereto, there being graduations upon the first and third sleeves coöperating with

graduations upon the third and second sleeve, the graduations on the first sleeve being visible through the opening in the second sleeve.

2. A micrometer caliper comprising a U-frame, a pair of spaced sleeves, one within 30 the other secured to one end of the frame, there being an opening in the outer sleeve, a sleeve movable between the two and having secured thereto a measuring spindle, said sleeve having graduations from fourths to 35 sixty-fourths of an inch adapted to coöperate with graduations in the inner and outer sleeve, there being graduations of one thousandths of an inch on the inner sleeve and coöperating with graduations on the movable 40 sleeve, the graduations on the sleeves being visible through the opening in the outer sleeve.

In testimony that I claim the foregoing I have hereunto set my hand at Milwaukee, 45 in the county of Milwaukee and State of Wisconsin.

FRANK H. MILLER.
